CUTTER FOR ASPHALT TILES AND THE LIKE

Charles A. Regele, Manheim Township,
Lancaster County, Pa.

Application November 9, 1949, Serial No. 126,305

7 Claims. (Cl. 164—57)

1

This invention relates to a cutter for asphalt tile and the like, and is directed particularly to a small portable hand-operated type of cutter which may be used by the installation mechanic on the job for shearing asphalt tiles or the like.

Asphalt tile compositions are relatively hard and tough. They are generally laid in the form of tiles secured to the supporting base by an adhesive. In order to provide a workmanlike installation, it is desirable to provide the tile with sharp, clean edges. As supplied to the layer from the factory, the tiles have such sharp, clean cut edges; but in practically every installation it is necessary to cut some of the tiles, due to the irregular shape of the room in which the tiles are installed, the presence of obstructions such as display counters or the like in stores, and other irregularities which necessitate the severance of certain of the tiles. In some types of border treatment a whole series of diagonally cut half tiles will be required, and these may be severed from full size tiles on the job.

The conventional cutters now on the market are adaptations of slate cutters, and their action is essentially a fracturing or breaking one rather than a shearing or severing action which is desirable in order to produce the required sharp edges.

An object of the invention is to provide a cutter for severing asphalt tile and the like which will perform a shearing operation and provide the severed tiles with sharp, square edges.

Another object of the invention is to provide a cutter which will satisfactorily sever asphalt tiles and the like by actual severance of the material through a portion at least of the thickness of the product prior to fracture.

Other objects of the invention will be clear from the following description of a preferred embodiment of the invention which is illustrated in the attached drawings, in which:

Figure 1 is a front elevational view of a cutter embodying the present invention;

Figure 2 is a top plan view of the cutter of Figure 1;

Figure 3 is a sectional view taken along the line III—III of Figure 1;

Figure 4 is an enlarged diagrammatic sectional view showing the cutting blades; and

2

Figure 5 is an enlarged detailed isometric view, partially in section, showing the action of the blades in severance.

Referring to the drawings, the device comprises a frame member 2 having a pair of legs 3 and 4. The frame includes a lower cross member 5 provided with a reinforcing platform 6, an upper cross support 7, and a pair of upright posts 8 and 9. The whole frame is preferably formed from a single malleable or grey iron casting. Referring to Figure 3, the lower cross member 5 is provided with a milled recess 10 which receives a lower stationary cutter bar 11. The cutter bar 11 is secured to the cross member 5 by machine screws 12 (Figure 1) which pass through slots 13 in the lower cutter bar 11 and are received in threaded openings provided in the cross member 5.

An upper movable cutter bar 14 is mounted in cooperative severing relationship with the lower cutter bar 11. The upper cutter bar 14 is "floated" from the upper cross member 7 by a machine screw 15 disposed approximately in the center longitudinally of the upper cutter bar 14. This machine screw 15 passes through a slotted opening 16 in the upper cutter bar and is received within a threaded opening in the upper cross support 7. A washer 17 is provided surrounding the shank of the machine screw 15 adjacent the head thereof, and a lock nut 18 is provided for holding the machine screw in adjusted position with the blade 14 pressed firmly against and in sliding engagement with a milled surface 19 provided on the upper cross support 7 to provide for accurate movement of the upper cutter bar 14 with respect to the lower stationary cutter bar 11, substantially free of lateral motion. Both the milled surfaces 10 and 19 are accurately machined to provide for close sliding engagement of the upper cutter bar 14 over the lower cutter bar 11. The outer ends of the upper cutter bar 14 are guided by flat steel plates 20 and 21 which are secured to the frame 2 by machine screws 22 and 23 which pass through drilled openings in the plates 20 and 21 and are received, as shown in Figure 2, within threaded openings in the upright posts 8 and 9. Lock nuts 24 are provided for holding the machine screws in adjusted position with the plates 20 and 21 disposed in proper spaced relationship with respect to the milled

surface 19 of the frame to permit the upper bar to slide freely along the milled surface 19 of the frame and the inside faces of plates 20 and 21. Spacers 25 shown in Figures 1 and 3 are provided between the lower cutter bar 11 and the plates 20 and 21 to position the plates 20 and 21 in parallelism with the milled surface 19.

Movement of the upper cutter bar 14 is effected through a pair of cams 26 and 27 which are connected together by an actuating bar 28 for simultaneous movement. The cams 26 and 27 are pivoted to the frame at the upright posts 8 and 9 by the machine screws 23 which serve to secure the upper ends of the plates 20 and 21 to the frame. The cams are made from plate steel, and their thickness corresponds to the thickness of the blade 14 so that when the unit is assembled the cams will be disposed between the milled surface 19 of the frame member and the flat surfaces of the plates 20 and 21 for free pivotal movement therebetween.

The pivots 23 for the cams 26 and 27 are so positioned that the upper cutter bar 14 will have its cutting edge inclined with respect to the cutting edge of the lower cutter bar 11. In the embodiment illustrated in Figure 1, the pivot 23 for the cam 26 is closer to the cutting edge of the lower cutter bar 11 than is the pivot for the cam 27. The cam 26 is provided with an extension 29 which receives an operating handle, not shown. As the handle is moved to the left in Figure 1, the connecting bar 28 is moved laterally of the movable cutter bar and the cams 26 and 27 are pivoted in unison about the screws 23, rivets 33 passing through the connecting bar 28 joining the cams 26 and 27 to the bar 28. The cam surfaces 31 which bear against the upper surface 32 of the upper cutter bar 14 are so shaped that a uniform downward motion is imparted to the upper cutter bar 14 without substantially changing the angular relationship of the cutting edge of the upper cutter bar 14 with respect to the cutting edge of the lower cutter bar 11, and thus the severing action is progressive along the length of the cutter bars. This is important in the severance of asphalt tile and similar materials of a relatively hard and tough character where a shearing action, as contrasted with a fracturing action, is desired in order to secure sharp, straight edges.

In order to return the blade to its upper position upon completion of the severing operation and return of the operating handle portion 29 to the position shown in Figure 1, there is provided a pair of return springs 33 and 34 which are pivotally attached to projecting rivets 35 secured to the upper cutter bar 14 and corresponding rivets 36 secured to the cam-connecting bar 28. This arrangement insures that the blade will be properly returned, for the action of the bar imparts a nonuniform tension to the springs and effects a slight rocking motion to the cutter bar. Any tendency for the blade to stick is thus avoided.

A guide arrangement is provided on the cutter as shown in Figures 2 and 3. It includes a rod 37 which is received within a screw threaded opening in a boss 38 formed on the lower cross member 5. A lock nut 39 is provided for securing the rod 37 in position with a flat surface 40 thereof disposed downwardly. A reversible guide 41 is mounted on the rod 37. The guide 41 has a projecting boss 42 provided with an opening 43 which receives the rod 37. The boss 42 is also provided with a threaded opening which receives

a thumb screw 44 which locks the guide in adjusted position on the rod 37.

As shown in Figure 2, the guide 41 has a pair of legs 45 which are disposed at a 90° angle with respect to one another. In the severance of diagonally cut tiles, a corner of the tile to be severed is disposed on a table surface 46 of the guide, with the projecting edges of the tile lying in engagement with the legs 45 and with the tile 19 extending through the opening between the cutter bars 11 and 14. The position of the guide 41 is adjusted along the rod 37 so as to cut the tiles into pieces of the desired dimensions. The guide 41 is reversible so as to present a surface 47 which will be disposed parallelly to the cutting edges of the cutter bars when the guide is positioned on the rod 37, and thus the severance of a multiplicity of tiles into rectangular-shaped pieces of desired dimensions will be facilitated. Once the guide 41 has been adjusted on the bar 37, it will be merely necessary for the operator to slide the individual tiles against the surface 47 and sever the tiles into pieces, one after another.

An improved severing action is obtained with the device of this invention if one of the cutter bars, preferably the movable upper one, is provided with a hollow ground edge as shown to enlarged scale in Figure 4 where the hollow ground edge has been indicated at 48. This may be accomplished by grinding the edge with a 6-inch diameter wheel disposed with its axis parallel to the length of the blade being ground. The illustration in Figure 4 is of a blade approximately one-quarter of an inch thick ground with such a wheel. The lower or stationary blade 11 may also be hollow ground, but this is not essential so long as the upper blade is hollow ground. Satisfactory results have been achieved with a flat ground blade 11 one-eighth of an inch wide and ground at an angle of 10° to the horizontal as indicated in Figure 4.

Referring to Figure 5, which diagrammatically illustrates the severing action by the upper blade 14 with its hollow ground cutting edge 48 and the lower blade 11 with its inclined cutting edge 49 disposed in severing relationship with a tile 50, it will be observed that the cutting edge 48 penetrates into the body of the tile 50 prior to any substantial penetration of the cutting edge 49 into the material. It will also be observed that, by reason of inclination of the cutting edge 49 along its length, the severing action is progressive along the length of the cut and thus hand severance of hard, tough materials with a sharp, clean cut edge is facilitated. In cutting asphalt tile, after severance has been effected through a portion of the thickness of the tile, a shearing action occurs which completes the cutting of the tile. Since there is a severing action as contrasted with a fracturing action at the upper surface at least of the tile, clean, sharp edges result at the upper surface of the tile where the joints between adjacent tiles are visible when the tile is installed. This type of severing action is not obtainable with the slate cutter type machines nor is it obtainable with flat ground severing members. It will be observed that the upper cutter bar 14 is free to pass over the surface of the lower cutter bar 11; and this assists in the attainment of a severing action or shearing action rather than the fracturing action which occurs when the movable blade is brought down through the piece to be cut, against a flat or recessed surface against which the blade is pressed.

I claim:

1. In a cutter for asphalt tile and the like, the combination of a frame, a stationary cutter bar fixed on the frame, a movable cutter bar mounted for sliding movement on the frame in shearing relationship with the stationary cutter bar with the cutting edges of said cutter bars being inclined in a single direction, one with respect to the other, means attaching said movable cutter bar to said frame for sliding and rocking movement with respect thereto in a fixed plane, means engageable with the movable cutter bar adjacent to each of the ends thereof to move the same in said fixed plane with respect to said stationary cutter bar with a substantially uniform motion to bring the cutting edge of the movable cutter bar progressively into shearing relationship with respect to the stationary cutter bar, and a spring acting on each end portion of said movable cutter bar and constituting the sole means for returning said movable cutter bar to normal position.

2. In a cutter for asphalt tile and the like, the combination of a frame, a stationary cutter bar fixed on the frame, a movable cutter bar mounted for sliding movement on the frame in shearing relationship with respect to the stationary cutter bar, means attaching said movable cutter bar to said frame for sliding and rocking movement with respect thereto in a fixed plane, a pair of cams pivoted to the frame above the movable cutter bar and engageable therewith adjacent to each of the ends thereof to move the same with respect to said stationary cutter bar with a substantially uniform motion, said cams having substantially equal throws and one being pivoted to said frame a greater distance from the cutting edge of the stationary cutter bar than the other to incline the cutting edge of said movable cutter bar in a single direction with respect to said cutting edge of the stationary cutter bar, means pivoted to said cams for connecting the same for coincidental pivotal movement, and a spring acting on each end portion of said movable cutter bar and constituting the sole means for returning said movable cutter bar to normal position.

3. In a cutter for asphalt tile and the like, the combination of a frame, a stationary cutter bar fixed on the frame, a movable cutter bar mounted on the frame for sliding movement in shearing relationship with said stationary cutter bar, means attaching said movable cutter bar to said frame for sliding and rocking movement in a fixed plane with respect thereto, a plurality of cams pivoted to the frame and engageable with said movable cutter bar to move the same with respect to said stationary cutter bar, a connecting bar pivoted to said cams for imparting coincidental pivotal movement thereto, and tension means disposed between said movable cutter bar and said connecting bar and constituting the sole connection between said movable cutter bar and its actuating cams.

4. In a cutter for asphalt tile and the like, the combination of a frame, a stationary cutter bar fixed on the frame, a movable cutter bar mounted on the frame for sliding movement in shearing relationship with said stationary cutter bar, means attaching said movable cutter bar to said frame for sliding and rocking movement in a fixed plane with respect thereto, a plurality of cams pivoted to the frame and engageable with said movable cutter bar to move the same with respect to said stationary cutter bar, a connecting bar pivoted to said cams for imparting coincidental pivotal movement thereto, and tension means disposed between said movable cutter bar and said connecting bar and constituting the sole connection between said movable cutter bar and its actuating cams.

5. In a cutter for asphalt tile and the like, the combination of a frame, a stationary cutter bar fixed on the frame, a movable cutter bar mounted for sliding movement on the frame in shearing relationship with said stationary cutter bar, a plurality of cams pivoted to the frame and engageable with said movable cutter bar to move the same with respect to said stationary cutter bar, a connecting bar pivoted to said cams for imparting coincidental pivotal movement thereto, and tension means disposed between said movable cutter bar and said connecting bar and constituting the sole connection between said movable cutter bar and its actuating cams.

6. In a cutter for asphalt tile and the like, the combination of a frame, a stationary cutter bar fixed on the frame, a movable cutter bar, a plurality of cams pivoted to the frame and engageable with said movable cutter bar to move the same with respect to said stationary cutter bar, a connecting bar pivoted to said cams for imparting coincidental pivotal movement thereto, and tension means disposed between said movable cutter bar and said connecting bar and constituting the sole connection between said movable cutter bar and its actuating cams, and means passing through a slot in said movable cutter bar and into said frame for attaching said movable cutter bar to said frame for sliding and rocking motion in a fixed plane with respect thereto.

7. In a cutter for asphalt tile and the like, the combination of a frame, a stationary cutter bar fixed on the frame, a movable cutter bar, guide plates secured to said frame overlying the ends of said movable cutter bar, means passing through an opening in said movable cutter bar and secured to said frame for attaching said movable cutter bar to said frame for sliding and rocking movement with respect thereto between said guide plates in a fixed plane substantially free of lateral movement, a plurality of cams pivoted to said frame and engageable with said movable cutter bar to move the same with respect to said stationary cutter bar with a substantially uniform motion, said cams having substantially equal throws and one being pivoted to said frame a greater distance from the cutting edge of the stationary cutter bar than another to incline the cutting edge of said movable cutter bar in a single direction with respect to said cutting edge of the stationary cutter bar, a connecting bar pivoted to said cams for imparting coincidental pivotal movement thereto, and a pair of tension springs connected to said movable cutter bar and said connecting bar at spaced points along the length of said movable cutter bar and said connecting bar to apply nonuniform tension to said movable cutter bar as said bars are moved, said springs constituting the sole means for returning said movable cutter bar to a normal position.

8. In a cutter for asphalt tile and the like, the combination of a frame, a stationary cutter bar fixed on the frame, a movable cutter bar mounted on the frame for sliding movement in shearing relationship with said stationary cutter bar, means attaching said movable cutter bar to said frame for sliding movement in a fixed plane with respect to said frame substantially free of lateral motion and free for slight rocking motion, a plurality of cams of substantially equal throws pivoted to said frame, said cams engaging said movable cutter bar to move the same with a substantially uniform motion with respect to said stationary cutter bar, a connecting bar pivoted to said cams for lateral movement with respect to said movable cutter bar to impart coincidental pivotal movement to said cams, and springs pivotally connected to said movable cutter bar and to said laterally movable pivoted connecting bar.

7
and acting on each end portion of said movable cutter bar to apply nonuniform tension to said movable cutter bar during return movement thereof to normal position, said springs constituting the sole means for returning said movable cutter bar to said normal position.

CHARLES A. REGELE.
